(57) **CLAIM**

The ornamental design for a child's drinking cup, as shown
and described.

DESCRIPTION

FIG. 1 is a perspective view of a child's drinking cup
according to the invention; and,

FIG. 2 is a right side elevation view of the child's drinking
cup of FIG. 1.

The broken lines shown in FIGS. 1 and 2 are for illustrative
purposes only and form no part of the claimed design.
